UNITED STATES PATENT OFFICE.

HOWARD BROADWELL, OF NEW YORK, N. Y., ASSIGNOR TO WESTERN ELECTRIC COMPANY, INCORPORATED, OF NEW YORK, N. Y., A CORPORATION OF NEW YORK.

LUBRICATING DEVICE.

Application filed October 3, 1922. Serial No. 592,046.

To all whom it may concern:

Be it known that I, HOWARD BROADWELL, a citizen of the United States, residing at New York, in the county of New York, 5 State of New York, have invented certain new and useful Improvements in Lubricating Devices, of which the following is a full, clear, concise, and exact description.

This invention relates to liquid ejectors, 10 and more particularly to devices for ejecting oil into machine bearings.

Its object is to provide a tool of this character by means of which each of a large number of bearings may be quickly oiled 15 with a predetermined small quantity of oil, with only one filling of the oil chamber.

To this end the invention comprises an oil gun having a piston rod and piston thereon, and a member adapted to be manually tensioned and released to drive the piston rod a predetermined distance forwardly in the oil chamber to eject a small quantity of oil from the nozzle of the gun and into the bearing of the machine, for 25 each releasing operation.

More specifically, the gun comprises a casing which encloses a threaded piston rod fixed therein against rotation but capable of longitudinal movement in the casing. 30 This movement is imparted to the piston rod by means of a ratchet wheel which is threaded thereto and fixed against longitudinal movement with respect to the piston rod. In setting the gun, tension is stored up in a

35 spring-retracted driving member by rotating the same manually by means of a knob attached thereto and projecting outside the casing, which knob, in the present embodiment, is rotated one revolution for each 40 setting of the gun. This driving member carries a pawl which during the rotation of the driving member rides idly over the ratchet teeth, a holding pawl normally engaging the teeth of the ratchet to maintain

45 said driving member advanced as it is rotated. The nozzle of the gun is then inserted in the bearing to be lubricated and the holding pawl is thrown out of engagement by pressure applied manually thereto, 50 and the ratchet is rapidly rotated one revolution on the threaded piston shaft which, since the shaft cannot rotate, is forced rapidly toward the nozzle a distance of approximately one thread, the piston head act-

ing on the oil in the chamber to eject or 55 squirt a small quantity of oil into the bearing with considerable force.

The oil gun of this invention is especially adapted for oiling ball bearings which are in use and which are inaccessible from above 60 and must be oiled from beneath the bearings, the end of the nozzle being turned at an angle to facilitate the oiling operation. In oiling bearings from below, gravity cannot be used to cause the oil to flow into the 65 bearing, but the oil must be squirted up with considerable force in order to lubricate the bearing effectively.

Referring to the drawings, Fig. 1 is a side elevation of the oil gun; Fig. 2 is a side view 70 partially in section; Figs. 3, 4 and 5 are sectional views on lines 3-3, 4-4, and 5-5, respectively, of Fig. 1.

Referring to the drawings, 1 designates a threaded piston rod or shaft which carries a 75 piston head 2. This piston head is fixed to the shaft by means of nuts 3. The oil chamber 4 is formed by a cylinder 5 having a nozzle 6 provided with a small hole 7 through which the oil is ejected into the bearing to be lubricated. The shaft or piston rod 1 is fixed against rotary movement by a screw 8 (Fig. 3) passing through the cylinder 5 and having an extension or tongue 9 (Figs. 2 and 3) projecting into a slot 10 (Fig. 2) running the length of the shaft. Screws 11 and 12 serve to hold a U-shaped member 13 rigidly connected to the cylindrical member 5. Mounted to rotate upon the shaft 1 is an interiorly threaded ratchet wheel 14. This ratchet wheel is prevented at one end from moving longitudinally on the shaft 1 by the extension 9 of screw 8. At its other end, this ratchet wheel rides against a cylinder 15 rotatably 90 mounted on shaft 1. This cylinder or tube is surrounded by a spiral spring 16 having one end fixed to the U-shaped member 13 at 17 and its other end fixed to the said cylinder at 34. A holding pawl 19 (Fig. 4) forming part of a spring pressed member 20 (Fig. 1) normally engages the teeth of the ratchet wheel 14. This member is fastened to the casing 21 by screws 22, 23 in such a manner that when pressure is applied upwardly as shown in Fig. 1 to member 20, the slots 24, 25 therein permit the member 100 to move upwardly whereupon the pawl 19

is disengaged from the ratchet wheel. A small length of piano wire 26 is staked to the cylinder 15 at one end and its other end is bent to lie between teeth of the ratchet 5 wheel 14 to form a driving pawl. This wire by abutting against a projection on a screw 28 extending through the member 13 holds the cylinder or tube 15 in its normal position.

In operating the oil gun, the knob or 10 knurled member 29 secured to the exposed end of cylinder 15 by a screw 40 is turned clockwise until the wire 26 abuts against the other side of the screw 28. The pawl 19 holds it in this position. This turning 15 movement stores up tension in the spiral spring 16. The nozzle 6 of the gun is then inserted in the bearing to be lubricated and the pawl 19 is disengaged from the ratchet wheel 14 by pressing the member 20 upwardly as shown in Fig. 1, thus permitting the tension of the spring 16 to rotate the ratchet wheel 14 by means of the pawl 26, in a counter-clockwise direction. Inasmuch 20 as the ratchet wheel 14 cannot move longitudinally, the shaft 1 on which it is threaded is forced to move toward the nozzle a distance of substantially one thread with such rapidity that the piston head 2 on the 25 end of the shaft forces a small quantity of the oil in the chamber 4 out through the nozzle opening 7 and into the part of the machine to be lubricated. The gun is similarly set and released for each bearing to be oiled, and at each releasing operation, the piston rod moves toward the nozzle a 30 distance equal substantially to one thread on the piston rod or shaft.

To reload the tool with oil, the screw 8 is first removed and the threaded shaft 1 is backed out of the chamber by turning 40 the shaft counter-clockwise by means of a pair of pliers applied to the flattened end 33 of the shaft. The screw 8 is then replaced and the screw 30 and the two washers 31, 32 at the nozzle end of the tool are removed. The oil chamber may then be filled to its maximum capacity with oil of the desired character. The washers 31, 32 and

screw 30 are then replaced and the tool is again ready for use. 50

What is claimed is:

1. A lubricating tool comprising a cylinder having a nozzle, a threaded piston rod projecting into said cylinder, a piston head thereon, means for holding the same against rotary movement, a ratchet wheel threaded thereon and held against longitudinal movement, a holding pawl normally engaging said ratchet wheel, a spring restored manually operable member having a pawl cooperating with said ratchet wheel, and means to release said holding pawl. 55

2. A liquid ejecting device comprising a casing having a nozzle, a threaded piston rod in said casing fixed against rotation, a piston head thereon, an oil chamber formed in said casing, a rotary element threaded thereon and fixed against longitudinal movement, a holding pawl normally engaging said element, a rotary driving member, 60 a spring for maintaining the same in normal position, a handle for turning said member, a pawl carried by said member and adapted to engage said rotary element when set, and means for releasing said holding 70 pawl. 75

3. A liquid ejecting device comprising a casing having a nozzle, a threaded shaft in said casing having a piston head and a slot extending lengthwise of said shaft, a fixed tongue engaging said slot, an oil chamber formed in said casing, a ratchet wheel threaded on said shaft and fixed against longitudinal movement thereon, a holding pawl normally engaging the same, a tubular element surrounding a part of said shaft and carrying a driving pawl adapted to ride idly over said ratchet wheel when said element is rotated, and a coiled spring surrounding said tubular element for placing 80 the same under stress. 85

In witness whereof, I hereunto subscribe my name this 30th day of September A. D., 1922.

HOWARD BROADWELL
